SAFETY CATCH

Frederick A. Ballou, Jr., Providence, R. I., assignor to B. A. Ballou & Co., Inc., a corporation of Rhode Island

Application December 6, 1935, Serial No. 53,176

2 Claims. (Cl. 24—157)

This invention relates to a safety catch, and has for one of its objects the provision of a catch which may be more easily operated by the finger of the user.

Another object of the invention is the provision of a catch which may be rolled around by the flesh of the finger instead of by means of the finger nail of the user.

Another object of the invention is the provision of means by which the rotor member of the catch will be less likely than heretofore to be held by solder which is used to attach the body portion of the catch to a support.

Another object of the invention is the provision of a rotor member which will be of less material without weakening the same at any vital points, whereby a saving of precious metal may be had.

With these and other objects in view, the invention consists of certain novel features of construction, as will be more fully described, and particularly pointed out in the appended claims.

In the accompanying drawing:

Fig. 1 is an end view of the safety catch with the rotor member in partially closed position;

Fig. 2 is a sectional view through the rotor member looking at the catch in the same direction as shown in Fig. 1;

Fig. 3 is a section on line 3—3 of Fig. 2; and

Fig. 4 is an end view of the rotor member with a slightly modified finger piece engaging portion.

It is customary when purchasing safety catches for the purchaser to specify the amount of clearance which he desired between the solder surface and the point of the rotor or part which rotates in the device which is nearest to the soldered surface at the time of soldering. It is well-known in the art that in the practical construction and operation of safety catches it is desirable to have the pin stem as close to the solder surface as is practical, and yet the neck portion between the base and the ears must be long enough so as to space the nearest point of the rotor a distance from the soldered surface sufficient so that the solder will not run into it. Heretofore, when attaching the previous catches to various articles, if the solder was found to run up into the device so as to cause the rotor to become attached and prevent its rotation, the catches would be rejected by the trade and returned in exchange for those having greater clearance; and in order to obviate such empirical practice, I have found it to be of advantage to provide a catch member having a base presenting a surface for attachment to an article by means of solder, and another

surface generally parallel to the front surface and spaced therefrom with a generally circular rotor member pivotally supported above the base and having an edge swingable close to the said second surface in which the ends of said arc are joined by an edge of a shorter radial extent from said pivot axis than the remainder of the edge whereby a certain relative position of said members will provide a substantial space between the nearest portion of the rotor member and the said second surface so that any film of solder over the second surface will not be elevated sufficiently to obstruct the pivotal relation of said members or cause the rotor to become attached to prevent its rotary action; and I have also provided a more closely coupled catch structure to present a shorter neck than is found in the previous catches of which I am aware yet may be soldered without obstructing the rotation of the rotor, thus effecting a material saving in precious metal where such catches are formed of solid gold; and the following is a more detailed description of the present embodiment of this invention, illustrating the preferred means by which these disadvantageous results may be accomplished:

With reference to the drawing, 10 designates the supporting structure to which the safety catch is attached, such for instance as a bar pin or some like structure. The base of the safety catch 11 is attached to the support 10 by solder 12. 30 The body portion of the safety catch comprises the base 11 with upstanding ears 13 and 14 usually integral with the base and folded therefrom, and there exists between the ears a portion forming the upper surface 15 of the base 11. A rotor member 16 is mounted in bearings in the ears 13 and 14 by reason of its trunnion portions 17 and 18 extending into recesses in these ears 19 and 20, while the main disk portion 21 of the rotor operates in the space 32 between the ears 13 and 14 and comes in close proximity to the surface 15 on the top of the base. A handle portion 23 extends upwardly from the disk portion 21 and is provided on its engaging surface with a plurality of projections 24 as shown in Fig. 2 or the surface of this handle may consist of a plurality of projections 25 and 26 as shown in Fig. 4 with deeper inwardly extending recesses between them, the handle portion being such that the plurality of projections present an extended frictional engaging surface to the flesh of the finger so that the finger may be pressed more or less flatly against this handle portion and then by movement in either direction will serve to roll the 55

rotor member of the safety catch in its bearings to or from closed or open position.

The handle in projecting from the disk portion 21 presents abutment surfaces 29 which will 5 alternately engage the edge of the base in the different positions of said disk to limit the movement of the rotor member so that the slot in the rotor will register with the slots in the ears in one certain position and will limit them to a 10 position out of such alignment or a locking position when rotated to its extreme limit in the opposite direction.

When soldering the safety catch in position it is usual that the handle or turning portion such 15 as 23 be positioned vertically upwardly such as shown in the figures of the drawing so that this handle portion will be spaced from the base and there will be less likelihood of solder flux causing an adherence of solder between the finger portion and the base should the two be in contact; and in order to further avoid any likelihood of solder tacking the lower portion of the 20 rotor to the base by reason of some stray solder flux engaging the same which on melting quickly flows between two closely adjacent portions 25 which are just out of contact, I cut off a portion of the rotor member as at 30 or so reduce the dimension of the stock as to provide a flat surface opposite the handle 23. Thus, when this 30 handle is in the position illustrated in the drawing, this flat surface will provide a wide clearance space between the rotor member and the base and prevent the flow of solder flux and solder following the same into the joint to tack 35 the two together as sometimes accidentally happens when no such large space is provided; and in this manner I am enabled to obtain less rejects after soldering and yet a catch which is very easily operated without the necessity of 40 definite engagement by the finger nail.

The foregoing description is directed solely towards the construction illustrated, but I desire it to be understood that I reserve the privi-

lege of resorting to all the mechanical changes to which the device is susceptible, the invention being defined and limited only by the terms of the appended claims.

I claim:

1. In a safety catch, a member having a base presenting a surface for attachment to an article by means of solder and presenting a second surface generally parallel to the front surface and spaced therefrom, a support for a rotor member extending from said base, a generally circular rotor member pivotally mounted on said support and having an arcuate edge along the major portion of its periphery with the pivot axis of the rotor as its center, said edge being swingable close to said second surface and said member having the ends of said arc joined by an edge of a shorter radial extent from said pivot axis than the said remainder of the edge whereby a certain relative position of said members provides a substantial space between the nearest portion of the rotor member and said second surface. 5 10 15 20

2. In combination with an ornamental support, a safety catch, a member having a base with a surface soldered to said article and presenting a second surface generally parallel to the first surface and spaced therefrom, a support for a rotor member extending from said base, a generally circular rotor member pivotally mounted on said support and having an arcuate edge along the major portion of its periphery with the pivot axis of the rotor as its center, said edge being swingable close to said second surface and said member having the ends of said arc joined by an edge of a shorter radial extent from said pivot axis than the remainder of the edge whereby a certain relative position of said members provides a substantial space between the nearest portion of the rotor member and said second surface, and a film of solder 30 35 40 over the second surface insufficient to obstruct the pivotal working relation of said members. 25
